COMBINED DRAFTING TABLE, BOOKCASE TABLE AND CABINET UNIT

Robert W. Meyer, Menomonee Falls, Wis., assignor to
Eldon Manufacturing Co., Inc., Mequon, Wis., a cor-
poration of Wisconsin

Original design application Dec. 22, 1966, Ser. No.
5,151. Divided and this application Jan. 29, 1968,
Ser. No. 11,192

Term of patent 14 years

Int. Cl. D6—01

U.S. CL. D33—7

FIG. 1 is a perspective view of a combined drafting table, bookcase table and cabinet unit of my invention.
FIG. 2 is a top plan view.

FIG. 3 is a left-side view as indicated by line 3—3 on FIG. 2.

FIG. 4 is a right-side view as indicated by line 4—4 on FIG. 2.

FIG. 5 is a back view as indicated by line 5—5 on FIG. 2.

This application is a division of my design application Ser. No. 5,151 filed Dec. 22, 1966 and now abandoned.

I claim:

The ornamental design of a combined drafting table, bookcase table and cabinet unit, substantially as shown.
